MEANS FOR VAPORIZING HYDROCARBON FUEL

Application filed May 2, 1922. Serial No. 557,832.

My invention relates to method and means for vaporizing hydro-carbon fuel, and has for its object the provision of a method and means for diverting or deflecting liquid 5 globules of hydro-carbon fuel from the main stream of mixed vapor and liquid and for breaking up or vaporizing said deflected or diverted globules and returning the vapor thus created to said main stream. It has 10 for a further object the provision of means for stratifying the hydro-carbon fuel in passage from the carburetor to the cylinder, and for breaking up and vaporizing relatively dense strata of said fuel without materially affecting the lightest strata thereof. It has for a further object the provision of a 15 manifold embodying a pre-heating device external to the principal fuel passage in said manifold, but exposed thereto. It has for a further object the enlargement of a portion 20 of the fuel passage of a manifold, and the division of such enlarged portion into parallel connecting chambers directed longitudinally of said manifold by the interposition 25 of a vaporizing screen between said chambers. Heretofore vaporizing screens or pre-heaters have been interposed transversely of the principal passage through the manifold, thus requiring the whole stream of 30 fuel to pass through them, including the fuel already vaporized as well as the denser particles, or liquid globules. Such prior method requires the expenditure of a comparatively large amount of electric current, 35 if the current is applied continuously. But while it is desirable at all times to pre-heat or otherwise break up the liquid globules of fuel flowing through the manifold, it is not necessary after the engine is running warmly, to materially pre-heat the stream of previously vaporized fuel. Further, it is undesirable, if avoidable, to interpose a retarding screen in the channel of the previously vaporized fuel. One of the objects of my invention is, therefore, to save electric current by using only so much as is necessary 45 to break up and vaporize the liquid globules of fuel. Another object is to bring said liquid globules into contact with the vaporizer without interposing a retarding screen

in the main channel of the previously vaporized fuel. With these and other objects in view, my invention consists of the structure, combinations and arrangements of parts hereinafter described and claimed.

In the drawings, Fig. 1 is a side elevation of a portion of the manifold between the carburetor and power cylinder of an internal explosion engine, showing my invention with the hereinafter described vaporizer removed. Fig. 2 is a reduced central vertical longitudinal section of my invention. Fig. 3 is a top plan view of Fig. 1. Fig. 4 is a side elevation of a screen frame forming part of said vaporizer. Fig. 5 is a side elevation of said screen. Fig. 6 is a transverse vertical section on the line A—B of Fig. 1. Fig. 7 is a front elevation of said screen frame. Fig. 8 is a front elevation of said screen. Fig. 9 is a side elevation of an insulating case containing said screen. Fig. 10 is a front elevation partly in section of said case, showing said screen therein.

In the drawings, 1, is a portion of a pipe line or manifold for conducting hydro-carbon fuel from a carburetor (not shown), to the power cylinder (not shown), which manifold contains the main stream passage 1^a. Formed on said manifold is a housing or saddle 1^b, containing a vaporizer chamber 1^c open at one side, as at 1^d, for the reception of a vaporizer X. Said chamber also opens downwardly into said main stream passage. The vaporizer may be of any suitable construction, and may comprise a heating element including a frame 2, provided with a central aperture 2^a and wound in any suitable manner across said aperture with wires 3 and 4 preferably connected in parallel to form a heating screen or screens, the grooves in said frame and the spaces between the wires from the periphery of said aperture to the outer edges of said frame being preferably filled with cement. Said heating element is positioned in an insulating case comprising the front and back recessed covers 5 and 6, having central apertures 5^a and 6^a adapted to register with the aperture 2^a of said heating element, into which case extend binding posts 7 and 8.

to the inner ends of which the terminals of the wires 3 and 4 are respectively secured in any suitable manner, as by solder. Said vaporizer is inserted in said housing, and 5 the outer opening into said housing is then closed by a cover 9, of any suitable material, through which said binding posts are adapted to extend. Said cover is preferably formed on or secured to the vaporizer, so 10 that when said housing cover is removed from the housing the vaporizer will be withdrawn by it. It will be observed that a considerable portion of the area of said vaporizer is preferably spaced from the forward wall and from the overhead wall of 15 said housing, whereby free circulation and flowage room for hydrocarbons and gases over and forward of said vaporizer is afforded.

20 An apertured boss 10, is preferably formed on the top of said housing, with which a primer of any suitable construction may be connected for the purpose of injecting a priming charge of fuel into said chamber 25 and upon said heater. The occasional need of choking the carburetor in order to secure a priming charge of rich fuel when starting the engine may thus be avoided.

In operation, the major part of the lighter 30 gases or vaporized hydro-carbons are drawn directly through the main stream passage without passing through said vaporizer or into said housing chamber, said lighter gases rising through the vertical limb of said 35 manifold and turning sharply into the horizontal limb thereof and flowing along the lower levels thereof, while the liquid globules are thrown upward to the upper levels and against or through the vaporizer when 40 they are broken up and vaporized by the heated wires of the vaporizer, or in some degree even by the impact with the cold wires in case the electric heating current is turned off. The vapor thus created by said 45 vaporizer is then drawn down from said housing chamber, or from the face of said vaporizer, into the main stream.

If desired, the aperture 2^a may also be 50 filled with cement after said screen wires have been wound on said frame, so as to form a baffle plate heater, against which the globules of oil will be violently thrown and vaporized, the vapor being deflected back into the main stream. This method has the 55 advantage of increasing the absorptive area of cement, which has been found to absorb a considerable amount of oil when cool or while cooling and to expel said oil as vapor as soon as the wires become a little heated. 60 In such case, however, enough space is preferably left over and around the edges of said vaporizer to permit a little circulation of fuel above said vaporizer.

Thus a large part of the vapor passes 65 through said main stream passage without

close approach to or material absorption of heat from said vaporizer, which is therefore required to provide only sufficient heat to vaporize the part of the stream which passes through or comes into contact with 70 it. The amount of current required for said vaporizer may therefore be considerably reduced.

It is obvious that said structure may be altered or modified in various particulars 75 within the spirit and scope of certain of my claims.

What I claim is:

1. A fuel vaporizing and mixing device 80 comprising an L-shaped gaseous fuel conduit having a discharge port and an intake port, an enlarged chamber located adjacent to the bend and formed on the upper wall of the conduit leading from the bend to the discharge port, said chamber having no part 85 of the same projecting into the conduit, an electric heated element mounted wholly within the chamber, said element being spaced from the back wall and from the side wall of the chamber nearest the discharge 90 port of the conduit, whereby the condensed particles of fuel in the fuel stream are thrown laterally against the electric heated element to be vaporized and be returned to 95 the fuel stream.

2. A fuel vaporizing and mixing device 100 comprising an inverted L-shaped conduit having a fuel intake port in one of its arms and a fuel discharge port in the other of its arms, of a chamber located adjacent the bend and formed on the wall of the discharge arm of the conduit approximately opposite said intake arm, an electrically heated element mounted within said chamber and disposed approximately at a right angle to 105 the intake arm of said conduit, said element being spaced from the back wall of said chamber, whereby condensed particles of fuel are thrown laterally of the stream in the discharge arm and against said heating element to be vaporized and returned to the fuel stream.

In testimony whereof, I hereunto affix my signature.
